UNITED STATES PATENT OFFICE.

WINTHROP K. HOWE, WILLIAM S. HENRY, AND FREDERICK N. HALL, OF ROCHESTER,
NEW YORK, ASSIGNORS TO GENERAL RAILWAY SIGNAL COMPANY, OF GATES, NEW
YORK, A CORPORATION OF NEW YORK.

SWITCH-MACHINE.

1,307,200.

Specification of Letters Patent. Patented June 17, 1919.

Application filed November 29, 1915. Serial No. 64,138.

To all whom it may concern:

Be it known that we, WINTHROP K. HOWE, WILLIAM S. HENRY, and FREDERICK N. HALL, citizens of the United States, and residents 5 of the city of Rochester, in the county of Monroe and State of New York, have invented a new and useful Switch-Machine, of which the following is a specification.

This invention relates to electrically operated switch machines for interlocking systems for railways.

One of the objects of this invention is to construct and arrange the parts of an electrically operated switch machine so that 15 these parts can be made strong and yet light, will occupy a small compass and will be readily accessible for inspection, adjustment or repair.

A further object is to devise an electrically operated switch machine which can be used in electric interlocking systems in which the indication current is derived from some source other than that generated by the motor itself, and which will operate 25 to prevent a false indication of its movement being given.

A further object is to construct the controlling devices for the motor which operates the switch machine so that said motor 30 can be reversed and the parts of the switch machine restored to their former positions at any time after the initial movement of the motor.

Other objects and advantages will appear 35 as the description of the invention progresses, and the novel features of the invention will be particularly pointed out in the appended claims.

The invention consists in the parts and in 40 the arrangements and combinations of parts, which are more fully set forth hereinafter.

In describing the invention in detail, reference is had to the accompanying drawing, wherein we have illustrated a preferred 45 physical embodiment of our invention, and wherein like characters of reference designate corresponding parts throughout the several views, and in which--

Figure 1 is a plan view of a switch layout 50 typical of well known construction, and shows a switch machine embodying the invention applied thereto; Fig. 2 is a tabular diagram which illustrates graphically the

times at which the different parts of the switch machine move during the movement 55 of the operating motor from its position of rest in one position of the switch to its other position of rest in the other position of the switch; Fig. 3 is a top plan view of the switch machine with the cover therefor removed; Fig. 4 is a vertical longitudinal section taken substantially on the median line of the switch machine, certain parts being shown in elevation for the sake of clearness; Fig. 5 is a longitudinal section through 60 the friction clutch which constitutes part of the switch machine; Fig. 6 is an enlarged plan view of a portion of the switch machine which is hereinafter termed the indication controlling mechanism; Fig. 7 is an 65 enlarged perspective view, diagrammatic in its nature, which shows the parts of the indication controlling mechanism, said parts being broken and spread apart vertically so as to show their relative arrangement and 70 positions; Fig. 8 is an enlarged plan view of the braking mechanism, said view being a horizontal section taken substantially on the line 8-8 in Fig. 4, certain parts being removed, the line of section being also indicated by the line 8-8 in Fig. 9; Fig. 9 is an 75 enlarged section taken transversely of the switch machine and shows the braking mechanism, said section being taken substantially on the line 9-9 in Fig. 8, said line 80 of section being also indicated by the line 9-9 in Fig. 3; Fig. 10 is a detail elevation of a brake hanger, said elevation being taken substantially on the line 10-10 in Fig. 9 and drawn to a larger scale than said Fig. 9; Fig. 11 is a vertical transverse section taken 85 substantially on the line 11-11 in Figs. 3 and 4, certain parts being broken away for the sake of clearness; and Figs. 12 to 15 are views, diagrammatic in their nature, which 90 show the different positions of the important operating parts of the switch machine during the operation of the switch from one of its positions to its other position.

Referring to the accompanying drawing, 100 Fig. 1 shows a switch machine embodying the invention applied to a switch layout typical of well known construction, in which the stock rails are designated by the numeral 1 and the movable switch points by the 105 numeral 2. The switch machine as a whole

is designated A, the parts thereof being mounted on a base plate B (see Figs. 3 and 4) which has perforated lugs 3 by means of which the switch machine A is fastened to the ties. The electric motor for moving the switch is preferably mounted in a separate casing 4 which is located at one end of the switch machine A, and which has an annular flange 5 fastened by bolts 6 to a similar flange of a spacing sleeve or housing 7, which is integral with the supporting frame of the switch machine. The switch points 2 are connected by the usual front rod 8 which is connected to the lock rod 9 in the usual manner; and in a similar way, the throw bar 10 of the switch machine A is connected to the throw rod 11 of the switch which extends through a bracket 12 fixed to a switch rod 13 connecting said switch points 2, adjustable locking nuts 14 on said throw rod 11 acting as stops to cause said throw rod to move the bracket 12 after a limited amount of free movement. The detector bar 15 is mounted on rocking links 16 in the usual way and is connected by a link 17 to one end of a lever 18 which is pivoted on a suitable fixed pivot, the other end of said lever 18 being connected to the locking bar 20 of the switch machine A. For convenience in description, the end of the switch machine A adjacent to the lever 18, and opposite to the motor casing 4, will be hereinafter termed the front end.

Referring to Figs. 3 and 4, the parts of the switch machine are supported in box-like frames or casings fastened to suitable bosses or lugs on the base plate B; and the first frame at the rear end of the machine adjacent to the motor is for the friction clutch K and the braking mechanism and comprises two parts 21 and 22 which are fastened together by tap bolts 23 and which are secured to the base plate B by other tap bolts 24-24 and 25-25, respectively. Integral with the rear wall of the frame 21 is a boss 26, which is bored to form a bearing for the driving shaft 27, suitable reduction gearing being interposed between the driving shaft 27 and the motor shaft 50 (not shown) if found necessary or desired, because of the relatively low torque exerted by some types of motor.

The driving shaft 27 is integral with or secured to a plate 28, which forms the end cap for a casing 29 of the friction clutch K which has a cylindrical portion constituting a brake drum 19, (see Fig. 5). Extending through the casing 29 of the friction clutch K is an operating shaft 30, one end of which is journaled in the end cap 28; and to the operating shaft 30 are fixed a number of friction disks 31, which are alternately arranged with other friction disks 32 secured to the casing 29, a spring 33 and an adjusting nut 34 serving to press said friction disks

31 and 32 together. The friction clutch is shown merely as an example of a suitable construction which can be used with the switch machine, but it is to be understood that other forms of friction clutches may be used if desired.

Secured to the base plate B near its middle by tap bolts 35 is a gear frame G which has integral with its side walls a cross brace 36, and which has a lengthwise brace 37 extending from the middle of said cross brace 36 to the middle of the rear end wall of said gear casing G, said braces 36 and 37 being spaced above the upper face of the base plate B so as to leave a space for the operating gears. A shaft 38 is journaled at its lower end in the base plate B and at its upper end in the lengthwise brace 37, and to this shaft 38 is fixed a bevel gear 39 which meshes with a bevel pinion 40 fixed to the shaft 30. Extending downwardly through the cross brace 36 near its middle is a stud bolt 41 which screws into a bearing stud 42 (see Fig. 4) having a rim or flange at its lower end; and mounted on this bearing stud 42 is a main driving gear 44 which meshes with a pinion 45 keyed to the shaft 38 a suitable washer 46 being interposed between the bearing stud 42 and the cross brace 36. A driving pin 47 is fixed to the main gear 44 and extends downwardly therefrom; and journaled on this driving pin 47 are two freely revoluble rollers 48 and 49.

The throw bar 10 of the switch machine is guided at each end in notches formed in the base plate B which are covered by lugs or caps 50 and 51 (see Fig. 3) integral with the gear frame G; and said throw bar 10 is formed with a jaw or yoke 52 between its ends which is guided by lugs 53 integral with said gear frame G and which has therein a U-shape notch 54 adapted to receive the upper roller 48 on the driving pin 47.

The locking bar 20 of the switch machine extends longitudinally thereof, being guided in suitable grooves formed in the base plate B, and has a wide head 55 at its rear end which rests upon a guiding surface 56 (see Fig. 3) formed on each side of the gear frame G, and which has a cam slot 57 therein of a general elliptical shape adapted to cooperate with the lower roller 49 on the driving pin 47. A locking dog 58 is secured to the locking bar 20 near its middle and is arranged to pass behind the sides of the yoke 52 of the throw bar 10 and thereby lock the said throw bar 10. Near the front end of the locking bar 20 is secured another locking dog 59 for locking the lock rod 9 of the switch. The locking dog 59 has in its rear end a rectangular notch 59¹ having beveled corners for the purpose hereinafter explained. The lock rod 9 is shown of the adjustable type comprising two bars 9^a arranged side by side and each having two 130

notches 60 and 61 in their lower edges, shown to the best advantage in Fig. 11 and Figs. 12 to 15; and these two bars 9^a are provided with adjusting nuts 9^b (see Fig. 1) by means of which said bars 9^a may be moved lengthwise relatively to each other. The two notches 60 and 61 in each of these bars 9^a are of different lengths, the long notch 61 in one bar being arranged opposite to the short notch 60 in the other bar, the short notch 60 in each case being just wide enough to receive the locking dog 59 without appreciable play. These bars 9^a constituting the lock rod, extend transversely of the base plate B of the switch machine near its front end and are guided near each side of said base plate by a cap 62 (see Fig. 3) of a supporting frame or casting L which is fastened by bolts 63 to the base plate B.

This supporting frame L has two upwardly extending lugs 64 and 65 integral therewith, and in these lugs is journaled a rock-shaft 66 which is pinned to a rocker-member 67 of substantially inverted Y-shape and having two operating arms (see Fig. 11). Secured to each of the bars 9^a of the lock rod 9 is a dog 68 which is arranged to engage the operating arms of the rocker-member 67 and to rock said rocker-member 67 and the rock-shaft 66 when the lock rod 9 is moved back and forth. The rear end portion of the rock-shaft 66 is square in cross section and straddling this end portion is the upper bifurcated end of a tripper arm 69 which is pivotally connected to said rock-shaft 66 by a pin 70, thereby permitting said tripper arm 69 to rock back and forth in a vertical plane longitudinally of the switch machine but causing said tripper arm 69 to move sidewise in correspondence with the movement of the rock-shaft 66.

Secured to the base plate B near the front end thereof is a box-like casing P, herein-after termed the pole-changer casing, which has a removable cover 71 and which contains the devices for controlling the operating and indication circuits of the switch machine. Near each end of the pole-changer casing P are two supporting blocks 72 which are fastened to lugs 73 (see Fig. 4) integral with the end walls of said pole-changer casing; and secured to the ends of said supporting blocks 72 are two contact supporting bars 74 of suitable insulating material to which are adjustably secured a plurality of contact springs 75. Extending across the pole-changer casing P and transversely of the base plate B are two parallel round rods 76 secured at their ends in any suitable manner to the side walls of said pole-changer casing; and slidably mounted on these rods 76 is a slide 77 to which is secured a block 78 of insulating material having embedded therein metallic contact pieces 79, the con-

tact supporting slide 77, together with the contact springs 75 and the contact pieces 79 constituting a pole-changer.

In the bottom of the pole-changer casing P is journaled a vertical shaft 80 (see Figs. 4, 5 and 7) at the upper end of which is fastened a pole-changer operating arm 81 which has a forked end straddling a downwardly projecting pin 82 secured to the slide 77 and which has two laterally extending lugs or projections 83 and 83¹. At the lower end of the shaft 80 and below the bottom of the pole-changer casing P a crank arm 84 is fastened to or integral with said shaft 80, which crank arm extends from said shaft 80 in the direction opposite to the direction in which said pole-changer operating arm 81 extends, and which has two laterally projecting knobs 85, substantially wedge-shape. Two guiding strips 86 are fastened by screws 85 or rivets to the upper face of the locking bar 20 so as to leave a space between them substantially equal to the distance between the outer edges of the knobs 85 of the crank arm 84, inclined shoulders 87 being formed on 90 the guiding strips 86 at their forward extremities for the purpose explained herein-after.

In front of the shaft 80 is a transversely extending carrier block 88 which is pivotally connected at its ends to two levers 90 and 90¹ journaled on pivot studs 91 integral with the base plate B, and which has two pins 92 and 92¹ each having an enlarged head, mounted loosely to slide in transverse bores 100 therein. The other ends of the levers 90 and 90¹, herein-after termed the indication levers, extend rearwardly into the path of movement of a pin 93 fixed in the yoke 52 of the throw bar 10. The pins 92 and 92¹ in the carrier block 88 are on a level with the projections 83 and 83¹ associated with the pole-changer operating arm 81 and also on a level with the upper part of the locking dog 59, and said pins 92 and 92¹ are also positioned 110 so as to be struck by the lower end of the tripper arm 69.

Referring more particularly to Figs. 3, 4, 8, 9, and 10, the braking mechanism is mounted in the frame for the friction clutch K and comprises two brake hangers H and H¹, one on each side of the brake drum 19, each of said brake hangers H and H¹ consisting of two side portions 94 (see Fig. 10), a lower connecting portion 95 and a cylindrical upper connecting portion 96. The parts associated with each of the brake hangers H and H¹ are constructed and arranged the same, and a description of one will suffice for both. The upper connecting portion 96 125 of each of the brake hangers H and H¹ is journaled on a shaft 97 which is supported at one end in a boss 98 integral with the outer end wall of the frame 21, and which is supported at its other end in a lug or projec- 130

- tion 99 integral with the inner end wall of said frame 21, said shaft 97 being held in place by being pinned to said lug 99. Each brake shoe comprises a brake block 100 and
- 5 a suitable brake lining 101 held in place on the concave face of said brake block 100 by upper and lower clamping plates 102 secured by screws to said brake block 100; and each brake shoe is pivotally connected by a pin
- 10 103 to the outer bifurcated end of a brake shoe supporting arm 104, which is fastened to a short shaft 105 by a pin 106, said shaft 105 being journaled in the side portions 94 of the corresponding brake hanger H or H¹.
- 15 Integral with the upper connecting portion 96 of each brake hanger H and H¹ is an arm 107 which extends outwardly in the direction away from the brake drum 19; and a tension spring 108 is hooked at one end in a hole
- 20 109 in the outer end of said arm 107 and at its other end around the pin 103 between the bifurcations of the outer end of the corresponding arm 104. The under face 110 of the upper connecting portion 96 of each
- 25 brake hanger H and H¹ is flattened to form a stop for limiting the upward movement of the corresponding brake shoe 100.
- Along each side portion 94 of each brake hanger H and H¹ near the lower end thereof, 30 is a ridge 111 forming a stop for a rectangular follower plate 112 interposed between said side portions 94 and loosely mounted on the cylindrical end portions of a brake operating rod 113 extending transversely of the
- 35 switch machine. The middle portion of the brake operating rod 113 is rectangular in cross section so as to leave shoulders which limit the movement of the follower plates 112 toward the middle of said rod 113. En-
- 40 circling each end portion of the brake operating rod 113 is a compression coil spring 114, one end of which bears against the corresponding follower plate 112, and the other end of which bears against a washer 115 held
- 45 in place on the corresponding end of said rod by a cotter pin 116. Integral with the base plate B are two pairs of upwardly projecting lugs or stops 117 and 117¹ which are arranged in the path of movement of the
- 50 lower connecting portions 95 of the brake hangers H and H¹ and which serve to limit the movement of said brake hangers in both directions. A downwardly projecting pin 118 is fixed in the brake operating rod 113
- 55 near the middle thereof; and journaled on a short bearing stud 119 integral with the base plate B is a brake lever 120, one end of which is forked and straddles the pin 118, and the other end of which has a finger 121
- 60 extending out into the path of movement of the upper roller 48 on the driving pin 47, said brake lever 120 having an arcuate slot 122 therein to clear the shaft 38 which supports the bevel gear 39 and the pinion 45.

The brake linings 101 of the brake shoes are 65 arranged to press against the surface of the brake drum 19 forming part of the casing 29 of the friction clutch.

A suitable cover for the whole machine is provided, said cover preferably comprising 70 two end castings 200 and an intermediate portion 201 of sheet metal (see Fig. 4).

The switch machine is designed to be controlled from a distant point by a suitable manually operable circuit controller, such as, 75 for example, the lever shown and described in the patent to John D. Taylor No. 752,127, dated February 16, 1914; and in practice the switch machine and its controlling lever are connected together by an arrangement of 80 controlling devices and circuits suitable for governing the operation of the switch machine, and for giving indications of such operations. One arrangement of controlling devices and circuits applicable to this switch 85 machine is disclosed in the application of Charles S. Bushnell, Serial No. 161,171 filed April 14, 1917.

Operation: The parts are shown in Figs. 3 to 12 inclusive in their normal position. 90 When the controlling lever is moved to the reverse indication position, as will be readily understood by those skilled in the art, current is supplied to the operating motor and it drives the shaft 27, and disregarding for the present the action of the braking mechanism, the friction clutch K drives the operating shaft 30 which in turn drives the main gear 44 by means of the bevel pinion 40 and the bevel gear 39 and pinion 45, thereby causing the driving pin 47 and the rollers 48 and 49 carried thereby to move in a circular path. Fig. 2 shows a table of the time of operation of the different parts of the switch machine, the horizontal distances in 100 this figure representing in degrees one complete revolution of the driving pin 47, and the vertical lines intersecting the different horizontal lines pointing out where a change is made in the operating part corresponding 110 to that horizontal line. Figs. 12 to 15, inclusive, show diagrammatically the positions at different points in one revolution of the main gear 47, of the throw bar 10, the brake lever 120, the locking bar 20, the lock rod 115 9, the indication lever 90 and 90¹ and the pole-changer operating arm 81.

In Fig. 12, the above mentioned parts are shown in their positions corresponding to the normal position of the switch, and when current is supplied to the motor to throw the switch from its normal position to its reverse position, the driving pin 47 will be moved in the direction indicated by the arrow X in this Fig. 12. During the arc of 120 the first few degrees (about 52°) of the movement of the driving pin 47, said driving pin moves freely without actuating

any of the parts of the switch machine, since the rear edge of the cam slot 57 in the head 55 of the locking bar 20 is formed on the arc of a circle concentric with the main gear 44. 5 This free run of the motor permits its armature to accelerate and attain such speed that the motor is able to develop its full power in the subsequent movement of the switch. After this free run of the motor armature 10 the lower roller 49 on the driving pin 47 strikes the front edge of the cam slot 57, and during the next part of the movement of said driving pin 47 (from about 52° to 137°) the locking bar 20 is moved forward. 15 During the first part of this movement of the locking bar 20 the inclined shoulder 87 on one of the guiding strips 86 secured to said locking bar engages the corresponding knob 85 of the crank arm 84, and as can be 20 seen to the best advantage in Fig. 7, causes the crank arm 84, the shaft 80 and the pole-changer operating arm 81 to be shifted to their middle positions, thereby moving the 25 contact pieces 79 on the block 78 of the pole-changer into a corresponding middle position and breaking both indication circuits.

About two-thirds of the movement of the locking bar 20 (from about 52° to 100°) is employed to draw the locking dogs 58 and 30 59 out of their locking position with reference to the throw bar 10 and the lock rod 9, respectively, the remaining movement of said locking bar 20 being idle as indicated in Fig. 2. This excess idle movement of the 35 locking bar 20 occurring after said locking bar has moved to its unlocking position is conveniently used for operating the detector-bar 15, the operation of which overlaps the operation of moving the throw bar 10. 40 through its idle movement, hereinafter described, so as to economize time and shorten the cycle of the operation of the switch machine.

Soon after the locking bar 20 has been 45 moved to its unlocking position, (at about 106°) the upper roller 48 on the driving pin 47 enters the notch 54 in the throw bar 10 and commences the movement of said throw bar, the position of the parts at this moment 50 being that shown in Fig. 13. Because of the lost motion connection between the throw rod 11 and the bracket 12 connected to the switch points 2, the first part of the movement of the throw bar 10 (from about 106° 55 to about 180°) is idle, this idle movement of the throw bar 10 permitting an adjustment of the extent of the throw of the switch points 2 without requiring any change in the total throw of the throw bar 10, and also permitting 60 the acceleration of the heavy throw bar 10 and its connected parts so that their momentum will aid the motor in loosening the switch points 2 and setting them into motion. The actual throwing of the switch 65 points 2 takes place during the movement of

the driving pin 47 from about 180° to about 258°, the exact extent of this movement of the driving pin 47 depending upon the amount of lost motion between the throw bar 10 and the switch points 2. 70

The switch points 2 move the lock rod 9 connected thereto, and the dogs 68 secured to the bars 9a of said lock rod strike the opposite lowered arm of the rocker-member 67, thereby rocking the rockshaft 66 and the 75 tripper arm 69 from the position shown in Figs. 3, 7, 11, 12 and 13 to their opposite position, shown in Fig. 14. Just before the throw bar 10 reaches the end of its reverse movement (at about 250°) the pin 93 secured 80 in the yoke 52 of said throw bar strikes the indication lever 90¹ corresponding to the reverse position of said yoke 52, and shifts the carrier block 88 to its other extreme to bring the pin 92¹ corresponding to the lever 85 90¹ opposite to the lower projection 83¹ of the pole changer operating lever 81, as shown in Fig. 14. The locking bar 20 commences its return movement a few degrees before the throw bar 10 and the switch points 2 90 have moved to their full reverse position, as indicated in the table shown in Fig. 2, this preliminary movement of the locking bar 20 serving to consume the idle movement of said locking bar, so that shortly after the 95 switch points 2 have been fully thrown to their reverse position (at about 258°) the locking bar 20 commences its locking movement.

During the final part of the locking movement of the locking bar 20 the locking dog 59 strikes the lower end of the tripper arm 69 and drives said tripper arm against the pin 92¹, which in turn shifts the pole-changer operating lever 81, thereby moving the contact pieces of said pole-changer to the extreme reverse position, opposite to that shown in Fig. 3, so as to interrupt the reverse operating circuit, and close contacts for the reverse indication circuit the positions of the parts at this moment being that shown in Fig. 15. 100

Although the operating current is cut off from the motor, the armature of this motor will continue to revolve due to its acquired momentum, and to obviate any serious results of this continued rotation of said armature, it is necessary to provide some means for arresting its movement. In the so-called "dynamic indication" interlocking system, the rotation of the motor is arrested by the generation of the indication current; but in some cases, for instance, where an alternating current motor or a low voltage direct current motor is used, it is impracticable to use "dynamic indication," and in such cases other means for arresting the rotation of the armature of the motor must be provided. In the switch machine embodying this invention, suitable braking mechanism is pro- 110 115 120 125 130

vided for arresting the movement of the armature of the motor after the switch has been thrown and locked up, which braking mechanism is operated mechanically by the 5 movement of the parts of the switch machine driven by the motor.

Referring particularly to Figs. 8, 9 and 10, after the switch has been fully thrown and locked up, and the parts of the switch 10 machine are in the position shown in Fig. 15, the driving pin 47 continues to move in the direction indicated by the arrow X in said Fig. 15, by reason of the momentum of the armature of the operating motor and 15 the connecting gearing and at about 334 degrees the upper roller 48 strikes the finger 121 of the brake lever 120, which is in its middle position shown in Fig. 15 for the reason pointed out hereinafter, and turns 20 the brake lever 120 counter-clockwise, so as to shift the brake operating rod 113 from its position shown in Fig. 9 to the right. During this movement of the brake operating rod 113 to the right the lefthand follower 25 plate 112 (see Fig. 9) strikes the ridges 111 on the side members 94 of the lefthand brake hanger H and swings said brake hanger to the right so as to bring the brake lining 101 on the lefthand brake shoe 100 into contact 30 with the brake drum 19. The gearing connection between the main driving gear 44 and the casing 29 of the friction clutch K is such that at this time the casing 29 of said friction clutch and the brake drum 19 are 35 being rotated by the momentum of the motor armature and its connected parts in the direction indicated by the arrow Y in Fig. 9. The friction between the brake drum 19 and the brake lining 101 causes the whole brake 40 shoe 100 to move upwardly, rocking the brake shoe supporting arm 104, until the upper end of said brake shoe strikes the flat under face 110 of the upper connecting portion 96 of the lefthand brake hanger H. As 45 the driving pin 47 is driven farther by the momentum of the armature of the motor and its connected parts, said driving pin pushes before it the finger 121 of the brake lever 120 and increases the compression of the left- 50 hand spring 114 and the pressure of the lefthand brake shoe 100 against the brake drum 19. In this way, the armature of the motor and its connected parts are automatically braked, and the parts can be adjusted 55 so that the driving pin 47 is brought to a stop at substantially the same point each time the switch is operated. The peculiar wedge-shape of the finger 121 of the brake lever 120 permits the arc of movement of 60 the driving pin 47 after it first strikes said finger to be greater than the corresponding arc of movement of the brake lever 120, so that the full brake pressure may be exerted for some time while the driving pin 47 is 65 moving.

The stops 117¹ shown to best advantage in Figs. 8 and 9, limit the outward movement of the brake hangers H and H¹ from the brake drum 19, so that any binding between the sides of the hangers and the corresponding follower plates 112 will not draw said brake hangers out of place. The stops 117 limit the inward movement of the brake hangers H and H¹ toward the brake drum 19, particularly when the corresponding 70 spring 114 is compressed and the brake shoe is forced to its lower position, as explained hereinafter.

Substantially the same movements of the different parts of the switch machine occur 80 when the switch is thrown from its reverse position to its normal position, and these movements can be easily followed by analogy to those involved in the movement of the switch from its normal position to its reverse position, the only difference being that the armature of the motor is driven in the opposite direction and the driving pin 47 also moves in the opposite direction. 85

Referring again to the operation of moving the switch from its normal position to its reverse position and particularly to the initial movement of the motor, while the switch machine is idle, the righthand brake shoe 100 is pressed tightly against the brake 90 drum 19 by reason of the fact that in the preceding movement of the switch from its reverse position to the normal position it now occupies, the finger 121 of the brake lever 120 was engaged by the roller 48 on the driving pin 47 and forced to the position shown in Fig. 8. The righthand brake shoe 100 is also in its upper position pressed against the upper connecting portion 96 of the corresponding brake hanger H¹ by reason of 100 the fact that in this preceding movement of the switch the brake drum 19 was rotated in the direction opposite to the direction indicated by the arrow Y in Fig. 9; and in this upper position of the brake shoe 100, the 105 brake shoe supporting arm 104 inclines upwardly from its pivot axis. In short, when the switch is in its normal position the righthand brake shoe is pressed tightly against the brake drum 19; and when the armature 110 of the motor is driven in the direction indicated by the arrow Y so as to throw the switch to its reverse position, the friction between the brake drum 19 and said righthand brake shoe 100 forces said brake shoe downwardly. An examination of Fig. 9 will 115 make it clear that the righthand brake shoe 100 in moving downwardly must also move inwardly toward the brake drum 19 and increase the pressure of its brake lining 101 120 against said brake drum, since the brake supporting arm 104 is swung from a position above the straight line connecting the axis of said brake drum and the pivot axis of said arm to a position below that straight 125 line. 130

line. Consequently, the first movement of the brake drum 19 by the motor meets with material opposition, and this assures that the switch will not be operated by any current 5 less than the full load operating current. After the motor has turned the brake drum 19 a few revolutions against the increased opposition of the braking mechanism, the driving pin 47 moves away from the finger 10 121 of the brake lever 120 and permits the right hand spring 114 to expand and relax the pressure of the right hand brake shoe 100 against said brake drum. When the driving pin 47 leaves engagement with the finger 15 121 of the brake lever 120, both of the brake hangers H and H¹ assume a vertical position in which neither of the brake shoes 100 exerts any pressure against the brake drum 19, and in which brake lever 120 assumes 20 a middle position as shown in Figs. 13 and 14. The right hand brake shoe 100, which is in its lower position by reason of the fact that it was previously forced down by the friction between its lining 101 and 25 the brake drum 19, is now returned by the spring 108 to its upper position.

One important feature of this invention resides in the means for preventing the giving of a false indication. Referring to Figs. 30 6 and 7 it can be seen that either the extreme normal or the reverse position of the pole changer depends upon the position of the lock rod 9, the completion of the locking movement of the locking bar 20, and the 35 completion of the movement of the throw bar 10. Consequently, complete correspondence in the movement of the throw bar 10, the locking bar 20 and the lock rod 9 is necessary to close the contacts on the pole changer 40 for establishing the indication circuit at the switch machine.

One example will serve to illustrate why this coöperation is made necessary according to this invention for obtaining an indication. 45 Assume that the switch is in its normal position and that, for some reason, the lock rod 9 is broken or disconnected; and further assume that the indication levers 90 and 90¹, together with their associated carrier block 50 88 and pins 92 and 92¹, are absent, so that the indication depends merely on the movement of the lock rod 9 and the completion of the locking movement of the locking bar 20. It should also be understood that it is 55 assumed that the parts are so constructed that the tripper arm 69 will act directly on the knobs 83 and 83¹ of the pole-changer operating arm 81. Considering the operation under these assumed conditions, when 60 the operating lever is moved to its reverse indication position, the operation of unlocking the switch and throwing the switch is the same as hereinbefore described, and since it is assumed that the lock rod 9 is broken or 65 disconnected, it remains stationary, and the

lock dog 59 of the locking bar 20 returns in the same notches which it formerly occupied. Also, since the lock rod 9 remains stationary, the tripper arm 69 remains in its former position; and in the final locking movement 70 of the locking bar 20, this tripper arm 69 engages the same projection 83 with which it was formerly in contact, and transmits the force applied to it by the locking bar 20 to the pole-changer operating arm 81 to restore 75 the pole-changer contact pieces back to their former or normal position. The reverse indication circuit is not completed, since the pole changer was not reversed. However, the operator, not having received an indication, would naturally throw his lever back to its normal position with the idea of making another attempt to reverse the switch; and since the pole changer contacts are in their normal position, and although the 80 switch is in its reverse position, a false indication is given attesting that the switch is in its normal position.

The operator relying on this indication and believing that the switch has returned to 90 its normal position, probably will make another attempt to throw the switch to its reverse position, but the switch is already in its reverse position; and consequently the armature of the motor, while it may endeavor to revolve, cannot cause an actual movement of any of the parts. Also, the braking mechanism is tightly set and any further movement of the motor in the direction to move the switch toward its reverse 95 position only sets the brakes harder, with the result that the motor would be injured or the fuses in the operating circuit would be blown. The net result is that the switch 100 is in its reverse position, while the lever is 105 in its normal position, and either the motor has been injured or the fuses in the normal operating circuit have been blown.

There is a further serious consequence, in that, even if the operator has been watchful 110 enough to notice, by reason of the failure of the motor to take full load operating current when he moved his lever back to its normal indication position, that a false indication has been given, his control over the switch is 115 lost, and he is neither able to get his lever to its full reverse position in correspondence with the switch, or to move the switch to its normal position; and consequently a serious delay will result. 120

In the switch machine embodying this invention, however, the above described conditions will not cause a false indication or other bad consequences. Assuming the same conditions as hereinbefore set forth, 125 although the lock rod 9 and the tripper arm 69 do not move when the switch moves and is thrown to its reverse position, the pin 93 on the throw bar 10 strikes the reverse indication lever 90¹ and shifts the carrier block 130

88 so that the pin 92 is out of the path of movement of said tripper arm; and consequently the final locking movement of the locking bar 20 causes no movement of the pole-changer operating arm 81. This arm 81 and the slide 77 of the pole-changer are in their middle position, to which they were moved by the coöperation of one of the beveled shoulders 87 with the corresponding 5 knob 85 of the crank arm 84, as hereinbefore described, with the result that both indication circuits are broken at the switch machine and both operating circuits are closed at the switch machine. The operator, not 10 receiving an indication upon throwing his lever to its reverse indication position, will probably return his lever to the normal indication position, whereupon the switch will be thrown back to its normal position, and 15 the parts being then in proper position to set up the normal indication circuit, a correct indication will be received. The same operation takes place in case the switch happens to be in its reverse position at the time the 20 lock rod 9 is broken or disconnected. In this way, a switch machine embodying this invention operates so that a broken or disconnected lock rod will not cause a false indication nor any difficulty in restoring the 25 switch back to its former position and using some other route. Instead of the lock rod 9 being broken or disconnected, the throw bar 10 may be broken or disconnected, or some of the operating parts may be broken 30 or deranged in some way so that the throw bar 10 is not moved when the switch machine 35 operates while the locking bar 20 is moved; but in these and other similar cases the same protection against false indication is afforded.

Various changes may be made in the construction of the switch machine shown and hereinbefore described without departing from the invention or the particular physical 45 embodiment thereof disclosed, as for instance, the well known track circuit and electric lock may be substituted for the detector bar. Also, alternating current may be used instead of direct current for operating 50 the switch machine, and the indication current may be derived from a local source at the switch machine. The features of the switch machine embodying this invention may be combined with other switch machines 55 of a different type and construction, and obviously the switch machine shown and herein described may be made a part of any suitable interlocking system, or of a system for the control of a single remote switch.

60 Although we have particularly described the construction of one physical embodiment of our invention, and explained the operation and principle thereof; nevertheless, we desire to have it understood that the form 65 selected is merely illustrative, but does not

exhaust the possible physical embodiments of the idea of means underlying our invention.

What we claim as new and desire to secure by Letters Patent of the United States, is:

1. A switch machine for operating movable switch points comprising a throw bar and a lock rod, a motor for locking and unlocking said lock rod and for moving said throw bar, circuit controlling means for selectively controlling the normal and reverse indication circuits of said switch machine, and means controlled jointly by said throw bar and said lock rod for operating said circuit controlling means. 75

2. A switch machine for operating movable switch points comprising a throw bar, a lock rod and a locking bar for locking said lock rod, a motor for actuating said locking bar and said throw bar, circuit controlling means for selectively controlling the normal and reverse indication circuits of said switch machine, a movable device actuated by the final locking movement of said locking bar, and means controlled by 80 said throw bar and operated by the movement of said device for governing said circuit controlling means. 85

3. A switch machine for operating movable switch points comprising a throw bar, a lock rod and a locking bar for locking said lock rod, a motor for operating said locking bar and said throw bar, circuit controlling means for selectively controlling the normal and reverse indication circuits of said switch machine and having two shifted positions, movable members arranged to actuate said circuit controlling means, means for supporting said members shifted by the movement of said throw bar 95 to a position in which one of said movable members can actuate said controlling means to one of its shifted positions, a movable device having two operated positions and arranged to contact selectively with said movable members, means controlled by said lock rod for shifting said device to its different operated positions in correspondence with the position of the switch points, and means operated by the final locking movement of said locking bar for actuating said device and thereby causing the operation of the corresponding movable member and said circuit controlling means. 100 105

4. A switch machine for operating movable switch points comprising a throw bar, a lock rod and a locking bar for locking said lock rod, a motor for actuating said locking bar and said throw bar, a circuit controller having two extreme positions and 115 a middle position, means actuated by the initial unlocking movement of said locking bar for shifting said circuit controller to its middle position, and means operated by the final movement of said locking bar and 120 125 130

dependent upon the movement of the throw bar for shifting said circuit controller to its extreme position opposite to which it formerly occupied.

- 5 5. A switch machine for operating movable switch points comprising a throw bar, a lock rod and a locking bar for locking said lock rod, a motor for actuating said locking bar and said throw bar, a circuit controller for selectively controlling the normal and reverse indication circuits of said switch machine and having two operated positions in each of which one of said indication circuits is closed, two movable members arranged to operate said circuit controller, said members having two positions corresponding to the operated positions of said circuit controller, and means associated with said locking bar and operated thereby for actuating said members, the correspondence of said members being necessary to obtain the operation of said circuit controller, one of said members being controlled by said lock rod and the other of said members being controlled by said throw bar.
- 10 6. A switch machine for operating movable switch points comprising a motor, a throw bar connecting the motor and the switch points, a separate movable member connected to the switch points, a controller having contacts governing normal and reverse indication circuits, and means controlled jointly by said throw bar and said movable member for selectively closing the contacts of said circuit controller.
- 15 7. A switch machine for operating movable switch points comprising a motor, a throw bar connecting the motor and said switch points, a separate movable member connected to the switch points, an indication circuit controller, and operating means for said circuit controller including an operating connection independently controlled by said throw bar and said movable member, whereby the operation of said circuit controller is dependent upon the throw bar and the movable member being in corresponding positions.
- 20 8. A switch machine for operating movable switch points comprising a motor and gearing operated thereby, a throw bar operated by said gearing and connected to said switch points, a circuit controller for selectively closing the indication circuits of said switch machine and having normal and reverse positions, a movable member operatively connected to said switch points and having normal and reverse positions in correspondence with the position of said switch points, a movable device operated by said throw bar and having normal and reverse positions in correspondence with the position of said throw bar, said movable device in its different positions being in the path
- 25 of movement of said movable member when the latter is in the corresponding position, means for locking said switch points, and means operated by the final locking movement of said last-mentioned means for actuating said movable member, and means for transmitting the movement of said movable device to said circuit controller.
- 30 9. A switch machine for operating movable switch points comprising a throw bar, a lock rod connected to the switch points, a locking bar for locking said lock rod, a motor for actuating said throw bar and said locking bar, a circuit controller including normal and reverse contacts for selectively closing the normal and reverse indication circuits, said circuit controller being operated by the initial unlocking movement of said locking bar to open both the normal and reverse contacts, and means operated by the final locking movement of said locking bar and dependent upon the movement of said throw bar and said lock rod for actuating said circuit controller to close the normal or reverse contacts corresponding to the position of the switch points.
- 35 10. A switch machine for operating movable switch points comprising a motor, a throw bar connecting the motor and the switch points, a lock rod connected to the switch points, a locking bar actuated by the motor and adapted to lock the lock rod, an indication circuit controller adapted to close contacts selectively in either of two operated positions and to open such contacts in a middle position, means operated by the initial unlocking movement of the locking bar for actuating said circuit controller to its middle position, and means effective upon the final locking movement of the locking bar to change the circuit controller to an operated position, said means comprising movable elements independently actuated by the throw bar and the lock rod in accordance with their respective positions and adapted to form an operating connection between the circuit controller and the locking bar.

- 40 11. A switch machine for operating movable switch points comprising a motor, a throw bar connecting the motor and the switch points, a lock rod connected to the switch points, a locking bar actuated by the motor and adapted to lock the lock rod, an indication circuit controller adapted to close contacts selectively in either of two operated positions and to open such contacts in a middle position, means for operating said circuit controller to an operated position upon the final locking movement of the locking bar, said means including movable elements adapted when in corresponding positions to establish an operating connection between the locking bar and the circuit controller, and means for caus-

- ing said movable elements to independently assume positions corresponding with the respective positions of the throw bar and the lock rod.
- 5 12. In a switch machine for operating movable switch points comprising a throw bar, a lock rod, a locking bar for holding said lock rod and a motor for actuating said throw bar and said locking bar, a circuit controller for selectively controlling the indication circuits for said switch machine, and means for operating said circuit controller, said means being adapted to cause the selection of said circuits to be dependent upon the position of the throw bar and the lock rod and upon the final locking movement of the locking bar.
- 10 13. In a switch machine for operating movable switch points comprising a throw bar, a lock rod, a locking bar for locking said lock rod, an indication circuit controller having two operated positions and a middle position, and means for causing said circuit controller to assume an operated position in accordance with the position of the switch points, said means being dependent upon the positions of the throw bar and lock rod for selection of the operated position of the circuit controller, and being operated by the final movement of the locking bar.
14. A switch machine for operating movable switch points comprising a throw bar, a lock rod, and a locking bar for locking said lock rod, a motor for actuating said locking bar and said throw bar, a circuit controller for selectively controlling the normal and reverse indication circuits of said switch machine and having two operated positions in each of which one of said indication circuits is closed, and a middle position in which both of said indication circuits are opened, means associated with said locking bar for operating said circuit controller to its middle position upon the initial unlocking movement of said locking bar, two movable members arranged to operate said circuit controller, said members having two positions corresponding to the operated positions of said circuit controller, and other means associated with said locking bar and operated thereby for actuating said members, the correspondence of said members being necessary to obtain the operation of said circuit controller, one of said members being controlled by said lock rod and the other of said members being controlled by said throw bar.
